CLAIM

The ornamental design for a television receiver, as shown and described.

DESCRIPTION

FIG. 1 is a front perspective view of a television receiver, showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is a rear perspective view thereof;

FIG. 9 is a front perspective view showing only a stand portion thereof;

FIG. 10 is a front view of the stand portion;

FIG. 11 is a rear view of the stand portion;

FIG. 12 is a left-side view of the stand portion;

FIG. 13 is a right-side view of the stand portion;

FIG. 14 is a top view of the stand portion;

FIG. 15 is a bottom view of the stand portion; and,

FIG. 16 is a rear perspective view of the stand portion.

The broken lines in the figures depict portions of the television receiver and form no part of the claimed design.
